UNITED STATES PATENT OFFICE.

CHRISTIAN J. STAHLY, OF GOSHEN, INDIANA.

SILO.

1,137,676.

Specification of Letters Patent. Patented Apr. 27, 1915.

Application filed March 30, 1914. Serial No. 828,345.

To all whom it may concern:

Be it known that I, CHRISTIAN J. STAHLY, a citizen of the United States, residing at Goshen, in the county of Elkhart and State 5 of Indiana, have invented new and useful Improvements in Silos, of which the following is a specification.

This invention relates to silos and more particularly to a combined extension and 10 roof structure therefor.

One of the principal objects of the invention is to provide a novel and effective device which may be converted readily from a roof forming structure into an extension of the 15 walls of the silo which will permit the silo to be filled to its maximum capacity after the ensilage has settled.

A further object of the invention is the provision of novel means operable from the 20 base of the silo for converting the roof into a settling extension or vice versa.

Still another object of the invention resides in the provision of a settling extension adapted to be converted into a roof and in 25 the manner of closing the central portion of the roof, all of which is accomplished at the base of the silo.

Further objects of the invention will appear as the following description is read in 30 connection with the accompanying drawing, which forms a part of this application, and in which:—

Figure 1 is a detail side elevation showing the parts in roof forming position. Fig. 2 35 is a similar view showing the parts arranged to form a settling extension. Fig. 3 is a vertical sectional view through Fig. 2. Fig. 4 is a vertical sectional view through Fig. 1. Fig. 5 is a horizontal section taken on the 40 line 5—5 of Fig. 2. Fig. 6 is an enlarged detail sectional view through the cap and its associated parts. Fig. 7 is a detail elevation of a fragmentary portion of the roof and extension forming sections. Fig. 8 is a detail 45 vertical sectional view showing the manner of connecting the sections with the silo. Fig. 9 is a detail horizontal section on an enlarged scale taken approximately on the line 5—5 of Fig. 2. Fig. 10 is a detail 50 sectional view showing the modified type of section mounting. Fig. 11 is a similar view showing a further modification.

Referring more particularly to the drawings, 1 represents an ordinary silo which may be constructed in any suitable manner 55 and which is preferably provided, as is usual, with a chute (not shown) inclosing suitable ladder rungs 2 and discharge openings for the ensilage. These discharge openings have not been shown but may be 60 arranged in any suitable points throughout the height of the silo and are placed in such positions as are found most desirable by the purchaser. The upper end of the silo has secured around its circumference a plurality 65 of brackets 3 having eyes 4 formed in their upper ends to receive the hinging or annular pivotal rod 5 to which the sections 6 are connected. These sections each comprise in general a substantially rectangular 70 piece of flexible metal pivotally connected upon one side to its adjoining section by an eye bolt 7 whose eye receives the rod 5 to pivotally connect the sections to the rod 75 so that they may have inward and outward movement, as will be readily understood. Each section is reinforced by converging angle irons 8 and 9, the latter terminating short of the lower end of the section to permit the overlapping of the offset end 10 by 80 the next adjoining section.

As shown in Fig. 1, the angle iron 8 on one section is adapted to engage the angle iron 9 on the adjoining section when the sections are folded into roof forming position. The angle irons are also provided to reinforce and prevent bending of that portion of each section between the angle irons, the remaining portion extending to the left of each angle iron 9 being adapted to flex 85 to permit of the collapsing of the sections and is here given the independent designation of "wing" and is especially indicated by the numeral 11. Each section is also hingedly connected to the pivoting rod or 90 bar 5 by means of a loop hinge 12 having its terminals overlapping and being constructed of spring metal so as to permit of the rod 5 being snapped over the under terminal of 95 the loop.

When the sections are arranged in extension forming position, as shown in Figs. 2 and 3, the wings 11 overlap the adjoining sections just sufficiently to prevent any 100

change in the relative relation of the sections, while when the sections are in roof forming position each wing is completely covered by the adjoining section and the 5 angle irons 8 on the edge of each section abut the angle irons 9 running diagonally across the sections and defining the body and wing of the sections.

In order that all of the sections may be 10 raised from roof forming to extension forming position or vice versa from the base of the silo, a vertical rod or tube 13 extends upwardly through the center of the silo to a point considerably above the top of the 15 same and is braced at its upper end to the walls of the silo by the brace bars 14. Secured to the upper end of this rod or tube is an extension 15 of somewhat smaller diameter which carries an ordinary weather 20 vane 16, as shown, and forms a support for the closing cap 17 which has a flanged lower end 18, as shown, to engage over all of the sections, as shown in Fig. 1. This cap is supported upon a pair of diametrically opposite rods 19 secured at their upper ends to the cap and at their lower ends being inwardly offset and slidably mounted in guides 20 secured to opposite sides of a sleeve 21 slidably mounted upon the rod 13. The 25 lower ends of the members 19 are upwardly turned so as to limit their upward movement in the guiding members 20 and carry suitable cable pulleys 22 which are preferably pivoted thereto. Passing over these 30 pulleys upon opposite sides of the sleeve 21 are cables 23 and 24 both of which extend downwardly over pulleys 25 and 26 upon the upper ends of the sections and over pulleys 27 and 28 upon the lower ends of the 35 sections and thence downwardly to a common winding drum 29 secured to the silo adjacent the base thereof. After passing through the pulleys 22 the cables 23 and 24 are extended over pulleys 30 and 31 secured 40 to opposite sides of the rod 13 at its upper end and thence passed downwardly over pulleys 32 and 33 on the sleeve 21, their ends being then attached to eye members 34 and 35 secured to the rod 13 on opposite sides 45 thereof and at right angles to the pulleys 30 and 31.

Pivots connected to the lower end of the sleeve 21 and radiating therefrom are a plurality of braces 36 which are pivotally connected at their outer ends to each of the sections. These braces assume the position shown in Fig. 3 when the sections are in extension forming position and assume the position shown in Fig. 4 when the sections 55 are in roof forming position. Upon a downward pull on the cables 23 and 24 the rods 19 and the attached cap 17 will be elevated until the hooked lower ends of the rods come into engagement with the rods

20. Further upward movement of the bars 65 independently of the sleeve 21 is thus prevented. In this position the cap member is sufficiently elevated above the sections to permit the spreading of the sections by the action of the braces 36. Upon a further 70 downward movement of the cables the sleeve 21 will be moved vertically upon the rod 13 from the position shown in Fig. 4 to the position shown in Fig. 3. All of the sections will thus be held in the position shown in 75 Fig. 5, thereby producing an extension of the silo which may be filled so as to provide for settling. In other words, when the ensilage is placed in the silo through the top of the same it will settle several feet in three 80 or four days. This makes it necessary to again open the silo so as to fill it to the top.

In using this device the ensilage may be filled in to the top of the extension and allowed to settle which will approximately fill 85 the silo to its top. The roof may then be closed by the reverse operation to that just described.

In the modification shown in Fig. 10 instead of utilizing a circular hinge rod for the 90 roof sections and allowing the sections to overhang the upper edge of the silo the structure shown in this figure may be employed. This embodies an annular angle iron secured upon the top of a deflecting flange or band as 95 shown. The deflecting flange or band may be mounted on top of or beneath the angle iron as is found most desirable.

In Fig. 11 a T-iron is shown in place of an angle iron.

100

What is claimed is:—

1. In a silo, a conical, sectional roof mounted thereon, pivotal connections between the sections and the silo, a rod passing through the roof and silo centrally thereof, 105 a cap arranged to cover the apex of the roof and slidably mounted upon the rod, a slid- 110 able member carried by the rod, a slid- able connection between the cap and the slid- able member, means to elevate the cap independ- 115 ent of the slidable member, and to elevate the cap and the slidable member simulta- neously, and means connecting the slidable member and the sections whereby when the slidable member is raised the sections will 120 be forced outwardly into circular, extension forming position.

2. In a silo, a conical sectional roof mounted thereon, said sections being pivotally connected together at their longitudinal 120 edges, pivotal connection between the sections and silo, a rod passing through the roof and silo centrally thereof, a flanged cap arranged to cover the apex of the roof and slidably mounted on the rod, a sleeve slid- 125 ably mounted on the rod, a slidable connec- tion between said sleeve and cap, flexible means to elevate the cap independent of the

sleeve and to elevate the cap and sleeve simultaneously, and links pivotally connecting said sleeve to said sections, whereby, when the sleeve is raised, the sections will 5 be forced outwardly into circular extension forming position.

In testimony whereof I affix my signature in presence of two witnesses.

CHRISTIAN J. STAHLY.
